UNITED STATES PATENT OFFICE

2,098,802

TELEPICTURE SYNCHRONIZING SYSTEM

William G. H. Finch, New York, N. Y.

Original application February 26, 1936, Serial No. 65,869, now Patent No. 2,047,863, dated July 14, 1936. Divided and this application April 6, 1936, Serial No. 72,991

8 Claims. (Cl. 179—69.5)

This invention relates to synchronization of the rotating drum of a telepicture receiver with synchronizing signals cyclically transmitted during the picture reception and is a division of my co-pending application Serial No. 65,869, filed February 26, 1936, which matured into Patent No. 2,047,863 on July 14, 1936.

In the transmission of pictures to remote points, it is essential that the receiver picture drum be in phase synchronization with the transmitter drum. Many attempts have been made to attain such phase synchronization. It is extremely desirable to provide a positive driving connection between the motor and the revolving drum to avoid any deleterious effects due to friction coupling. In my Reissue Patent No. 19,575, I have disclosed a system for connecting and disconnecting the positive driving connection between the driving motor and the drum in response to synchronizing signals to maintain phase synchronization. In my present invention I utilize an over-running or positive clutch with means responsive to the synchronizing signals for maintaining the drum in phase synchronization. In one embodiment I revolve the receiving drum at a slightly higher rate than the transmitter drum, in the ratio of 101 to 100, so as to establish the synchronizing pulse at a predetermined portion of the receiving drum, which portion will accordingly always be in position due to the increased speed ratio, to receive the synchronizing impulse.

To overcome the effects of rotational inertia present in a large telepicture system having a large revolving drum, I provide a flexible mechanical coupling between the positive clutch and the receiving drum which permits momentary phase displacement due to accelerating or decelerating inertial forces and promptly automatically compensates for momentary phase displacements.

It is accordingly an object of my present invention to provide a novel telepicture synchronizing system utilizing an overrunning or positive clutch at the receiving station.

Another object of my invention is to provide a mechanical flexible coupling in the positive drive for a revolving drum, which automatically compensates for any momentary phase displacement due to acceleration or deceleration forces.

A further object of my invention is to provide novel electromechanical clutch engaging and disengaging means, operative in response to synchronizing signals for maintaining the revolving drum in phase synchronization.

Other objects of my invention together with

the foregoing will become apparent in the following description in connection with the drawings in which:

Figure 1 is a plan view of a preferred embodiment of the telepicture receiver.

Figure 2 is an enlarged broken cross-sectional view through the receiver drum and drive of Figure 1.

Figure 3 is a cross-sectional view through Figure 2 showing a partially enlarged plan view of 10 the drive mechanism and clutch trip levers.

Figure 4 is a perspective disassembled view of the clutch mechanism.

Figure 5 is a cross-sectional view illustrating a fragmentary detail of the internal clutch roller 15 assembly.

Figures 6, 7 and 8 are cross-sectional views taken respectively along 6—6, 7—7 and 8—8 of Figure 2 showing details of the synchronizing clutch control mechanism.

Figure 9 is a modification of the synchronizing clutch control mechanism corresponding to Figure 7.

Figure 10 is a cross-sectional view along 10—10 of Figure 9.

Referring to Figure 1, the telepicture receiver is mounted on a cast iron base 11 if it is designed for non-portable use. Synchronous motor 12 drives the receiver drum 13 through the overrunning clutch 14 and suitable gearing contained 30 in housing 15. Synchronous motor 12 is connected by leads 16 to electrical supply lines 17 for electrical energization thereof. Reduction gearing 18 connects worm or feed screw 19 to spindle end 20 rotating with drum 13. If drum 13 rotates 100 revolutions per minute and 100 scanning lines per inch are used, the pitch of worm 19 and its rate of revolution will be designed to advance receiver carriage 21 at the rate of one inch per minute so that the scanning of the film 40 22 mounted on drum 13 will progress in a continuous helical path. The light beam 23 emanating from focusing system 24 in this example is designed to be .01 of an inch in width to prevent translation overlapping. Carriage 21 45 houses the receiver electro-optical system and rides on V-tracks 25 and 26 with V-rollers 27 and 28.

The record sheet 22 is clamped upon drum 13 by clamping members 30. A scale is marked upon 50 the drum in the "underlap" portion to indicate the length of the record sheet being used. The plurality of roller sections 31 are shown out of position and are used to aid in smoothly mounting record sheet 22 on drum 13 in a manner de- 55

scribed in the parent application already referred to. Drum 13 is rotatably supported by pointed spindle 32 supported in tail stock 33.

Figure 2 is the broken cross-sectional view of Figure 1 through the axis of drum 13, illustrating in detail the mechanism for driving and mounting drum 13. The shaft 34 driven by the motor 12 through the flexible coupling 35 rotates worm 36 which drives worm gear 37. The hub 38 of worm gear 37 is connected to the clutch driver 40 by projections 41 of the hub 38 into corresponding grooves in the clutch driver 40. The worm gear 37 and the clutch driver 40 are free to rotate upon the spindle 42. The housing 15 encloses the worm and pinion drive and contains bearing 43 which supports one end of the spindle 42. The opposite end 44 of spindle 42 is conical and coacts with the metallic insert 45 pinned to end plate 46 of drum 13 by pin 47, and supports drum 13. Metallic insert 47 attached to opposite end plate 48 coacts with the conical end 49 of the spindle 32 supported in tail stock 33. Hollow shaft 50 rigidly connects the metallic inserts 45 and 47. Drum 13 is accordingly rotatably supported by the conical ends 44 and 49.

Figure 4 is a perspective illustration of the overrunning clutch 14 disassembled to more clearly explain its operation. The clutch cam plate 51 is rotatably mounted within the clutch driver 40 upon spindle 42 (shown in dotted). There are four openings 52 on the surface of the cam plate which contain metal cylindrical rollers 53. The clutch stop plate 54 is fitted adjacent to the cam plate 51 and contains four pins 55 which coact with the cylindrical rollers 53.

Figure 6 is a sectional view through the overrunning clutch 14 taken along 6-6 of Figure 2 illustrating the character of the recesses 52 in the cam plate 51. The principle of the overrunning clutch is well known in the art. The rollers 53 are wedged between the inner surface 56 of the clutch driver 40 and the inclined surfaces 57 of the recesses 52. Plungers 58 set in cam plate 51 are forced against each roller 53 by springs 59 set within the cam plate 51. The wedging action of the rollers 53 between surface 56 and inclined surfaces 57 serves as a positive connection between the clutch driver 40 and the cam plate or clutch driven member 51.

Figure 5 is a cross-sectional enlarged detailed view illustrating the arrangement of a roller 53 and its stop plate pin 55 within a recess 52 of the cam plate 51 in engaged position where the plunger 58 is pressed against the roller 53 by spring 59 set in the cam plate 51.

Referring to Figures 2 and 4, the hub 60 of cam plate 51 has a V notch 61 at one end thereof which coacts with a V projection 62 in the coupling member 63. Coupling member 63 has keyways 64 that slidably engage corresponding keys 65 set in the spindle 42. It is to be understood that the coupling member 63 is slidably axially on the spindle 42 and that this coupling member 63 provides the driving connection for the spindle 42 since no relative angular movement therebetween is possible.

Accordingly, when the overrunning clutch 14 is engaged the motor drive 12 is transmitted by the worm and pinion 36-37, the engaged clutch 14 and the coupling member 63 to the spindle 42. The face plate driver 66 is rigidly mounted on the spindle 42 by pin 67. A projection or key 68, on the face 69 of the face plate driver 66 sets into a corresponding groove in the end plate 46 of the receiver drum 13. A positive driving connection

is accordingly had between the motor 12 and the receiver drum 13 when the positive or overrunning clutch 14 is engaged.

A set of pins 70 project from the opposite end 71 of the face plate driver 66 to press the coupling member 63 into engagement with the V notches 61 of the cam 51. Springs 72 press the pins 70 against the face 73 of the coupling member 63. A positive driving connection of coupling member 63 with cam plate hub 60 is had for all practical purposes in the operation of the system since the pins 70 maintain the engagement of V projection 62 and V grooves 61 during the driving cycle of the drum.

An important feature of my present invention resides in the automatic connection and disconnection of the positive or overrunning clutch 14 to maintain the revolving receiver drum 13 in phase synchronization with the transmitter drum (not shown). In my Re. Patent No. 19,575, is described one method for connecting and disconnecting the positive drive from between the source of motive power and the revolving drum. My present invention embodies the principle of the overrunning clutch in an instantaneous synchronization mechanism. Synchronization according to Re. Patent No. 19,575 depends upon the actuation of a pawl engaging a ratchet wheel in the positive driving connection. The limits of phasing positions are accordingly within the pitch or width of one tooth of the ratchet wheel.

By employing an overrunning clutch, the positive drive is had during the rotation of the drum 13 and accurate phase synchronization is feasible at any point in the circumferential movement of the drum. The stop plate 54 contains the pins 55 which coact with the wedging rollers 53. When the cam plate 51 is driven by the clutch driver 40 during the wedging action of the rollers 53, the stop plate 54 is also driven and revolves with the cam plate 51. However, I provide a notch 74 on the periphery of the stop plate 54 which is engageable with a projection 75 on trigger lever 76 (Figure 7) which is mechanically biased by spring 77 toward the stop plate 54.

Figure 7 illustrates the engagement of lever projection 75 with the corresponding notch 74 in the stop plate 54. In this position the stop plate is prevented from further rotating counter-clockwise, as indicated by the arrow. The pins 55 accordingly abut the rollers 53 within the overrunning clutch 14 and force the rollers 53 against the plungers 58 to disengage the clutch 14, as will be understood by those skilled in the art. The rollers 53 are moved along the inclined surfaces 57 releasing the wedging action of the rollers 53 from between the cam plate 51 and the inner clutch driver surface 56. The motor 12 continues to rotate the clutch driver 40 but the driving of the drum 13 therefrom is instantaneously discontinued.

A pawl 80 is mechanically biased toward the stop plate 54 by spring 81. Pawl 80 projects into a notch 82 on the periphery of stop plate 54 at the instant the projection 75 of the trigger lever 76 engages the notch 74 in the stop plate 54. The pawl 80 accordingly prevents rebound of the stop plate when its notch is arrested, thus insuring a positive disengagement of the overrunning clutch 14.

Figures 3, 7 and 8 illustrate one modification for actuating the clutch 14 in response to synchronizing signals. For rapid engagement of the overrunning clutch 14 in response to synchronizing signals, falling weight 83 is caused to impact

the end 84 of the trigger lever 76, removing the projection 75 from the notch 74 in the stop plate 54 and permitting the plungers 58 to wedge the rollers 53 between the cam plate 51 and the clutch driver 40. The movement of weight 83 is guided by post 85 through a hole in the center of the weight 83.

Figure 7 illustrates the weight in its upper position. A projection 86 on the armature 87 of the synchronizing magnet 88 holds the weight 83 in its upper position in readiness for release. When a synchronizing impulse is impressed upon magnet 88 through its leads 89-90 in a manner well known in the art and described in detail in the parent application, the armature is attracted toward the magnet 88 against the spring 91 permitting the weight 83 to drop and impact the end 84 of trigger lever 76 to drivingly engage the clutch 14 as illustrated in Figure 8.

The weight 83 is replaced to its upper position by means of the lever 92. A pin 94 projects from the surface of the stop plate 54 and once per revolution of the stop plate, the pin 94 presses the end 93 of lever 92 downward so that the opposite end 95 automatically raises the weight 83 to its upper position shown in dotted in Figure 8. Spring 91 moves the armature 87 away from the magnet 88 permitting the projection 86 to engage the bottom corner of the weight 83 to hold it in its upper position in readiness for its cyclical release. Figure 3 is a sectional view through Figure 2 showing the driving connections from the motor coupling 35 and is a plan view of the synchronizing levers 76 and 92, weight 83 and magnet 88.

The receiver drum 13 is maintained in phase synchronism by means of cyclically transmitted synchronizing signals during the underlap period of the transmitter drum (not shown). The receiver synchronizing cam 100 is mounted at the end 20 of the spindle 42 outside the housing 15 clearly illustrated in Figure 2. The subtended angle of the cam nib 101 may be made equal to the corresponding subtended angle of the underlap portion of the receiver drum 13 so that the receiver synchronizing switch 102 will be maintained open during this interval to cause synchronizing magnet 88 to be connected in the circuit of the receiver amplifier output as described in the parent application.

As there described, the amplifier is a class B amplifier and the tubes are biased to "cut off", so that when no signal is impressed in the input circuit, zero plate current will flow and the synchronizing magnet 88 connected therein will not be energized until the synchronizing impulse is impressed. In my preferred embodiment, the synchronizing impulse is of a magnitude greater than the largest telepicture signal so that the synchronizing magnet will respond only to the synchronizing signals.

The parts of the receiver drum 13 are preferably made of aluminum to reduce its rotational inertia. The coupling member 63 coaxing with the driven cam plate 51 of the overrunning clutch 14 acts as a shock absorber to resist the inertial resistance of the drum 13 during its starting from rest to synchronous speed, or of any inertial forces it may present during the synchronizing action.

When there is a tendency for the cam plate 51 to advance in phase with respect to the coupling member 63, the coupling member will slide axially along the spindle 42 away from the clutch cam plate 51 and against the pressure of the pins 70 mechanically biased by springs 72. The V notches 61 of the cam hub 60, coaxing with the

V projections 62 of the coupling member 63, effects a positive driving action between the two when they are in engagement. A relative motion between the cam plate 51 and member 63 causes its V projection to slide away from the V notches 61 proportional to the forces tending to resist their in-phase movement. Such forces occur momentarily, and the coupling member 63 is again forced into normal engagement with the V notches 61 by the pins 70.

Any momentary relative movement between the clutch driven member 51 and the member 63 is automatically compensated by the return of the V projections 62 into normal engagement with the V notches 61. A spring 105 connects an eyelet pin 106 secured in the coupling member 63 and another eyelet pin 107 secured in the hub 60 of the cam plate 51, as illustrated in Figures 7 and 8. Spring 105 facilitates the automatic return engagement of the V projection 62 in the V notches 61 of the corresponding members.

Since the coupling member 63 is slidably keyed or splined to the spindle 42 and the face plate driver 66 is rigidly keyed to the spindle 42, the receiver drum 13 is driven positively from the coupling member 63. The source of motive power 12 is connected positively to the clutch driver 40 as already described. When the clutch 14 is engaged, a further positive connection is had between the clutch driver 40 and the cam plate 51, by the wedging action of the rollers 53. The V connection between the hub 60 of cam plate 51 and the coupling member 63 is in effect a flexible positive coupling.

When the projections 62 normally engage notches 61, the source of motive power 12 drives the receiver drum 13 through a positive driving connection. The relation of the hub 60 and coupling member 63 as already described is a flexible positive connection since it permits momentary changes in phase, but automatically returns to the normal phase relation. The synchronizing apparatus operating on the clutch stop plate 54 disconnects the positive driving connection between the source of motive power 12 and the receiving drum 13 at the positive or overrunning clutch 14 if the receiver drum 13 is not in phase synchronism with the transmitter drum (not shown).

It is to be understood that the receiver drum 13 rotates in synchronism and in phase with the corresponding transmitter drum, and that the carriage 21 simultaneously advances the impinging signal light beam 23 axially along the film 22 mounted on the drum 13 to record the picture being transmitted. The intensity of the light beam 23 sharply focused upon the film 22 varies in accordance with the shading of the picture being transmitted as is evident to those skilled in the art.

A modification of the synchronizing magnet-clutch trigger arrangement is illustrated in Fig. 9 corresponding to Fig. 7. The synchronizing magnet 110 corresponding to magnet 88 is mounted on a bracket 111 below the surface 112 of the base 11. The poles 113 of the synchronizing magnet 110 project through the surface 112 to coat with the armature plate 114 attached to the end 115 of the trigger lever 76.

Figure 10 is a cross-sectional view through the magnet 110 illustrating how the armature plate 114 is arranged above the two poles 113-113 of the electromagnet 110 and how the trigger end 115 is positioned between the poles 113-113. The trigger 76 is accordingly directly actuated by the synchronizing magnet 110 without the use of a 75

falling weight 83 as in the hereinabove described modification. While the clutch 14 and stop-plate 54 are rotating, the lever 76 will be held in the dotted position of Fig. 9 so that the armature plate 114 will be close to the poles 113 of the magnet 110. The peripheral surface of the stop-plate 54 will abut the trigger projection 75 and press the lever 76 toward the poles 113 against the action of the biasing spring 77. The armature plate 114 will accordingly be close to the poles 113 of the magnet 110 during the major portion of the revolution of the stop-plate 54, but will tend to be moved away under the action of spring 77 when the notch 74 comes in engaging position with the projection 75 of the trigger 76.

If the drum 13 is in phase synchronism, the synchronizing impulses will arrive at the synchronizing magnet 111 thru leads 116-117 in time to hold the trigger 76 away from engagement with the stop-plate notch 74 and permit the drum 13 to continue in phase synchronism. It is to be understood that if the drum 13 is out of phase synchronism, the notch 74 will engage the trigger projection 75 to disengage the positive or overrunning clutch 14. When the synchronizing signal is received by the magnet 110 the stop-plate 54 is released and the clutch engages to rotate the drum in proper phase synchronism.

30 I claim:

1. In a signalling system, a source of motive power; a driven member; a driving connection between said source of motive power and said driven member including means carried by said driving connection for disengaging said driving connection when said means is held against rotation; mechanism for arresting the rotation of said means when said driven member approaches a predetermined angular position; a synchronizing magnet responsive to received cyclic synchronizing signals; and a weight positioned above said mechanism, releasable by said magnet against said mechanism for rendering said arresting mechanism ineffectual during synchronous condition.

45 2. In a signalling system, a motor; a rotatable member; a clutch connecting said motor and said rotatable member including a disc carried by said clutch for disengaging said clutch when said disc is held against rotation; mechanism for arresting the rotation of said disc when said rotatable member approaches a predetermined angular position comprising a lever containing a projection mechanically biased against the periphery of said disc for engaging a notch on said periphery to disengage said clutch; a synchronizing magnet responsive to received cyclic synchronizing signals; and a weight positioned above said lever, releasable by said magnet against said lever for moving said lever projection away from said periphery to permit rotation of said rotatable member in synchronous condition.

50 3. In a telepicture system, a motor; a scanner; a positive driving connection between said motor and said scanner including means carried by said driving connection for disengaging said driving connection when said means is held against rotation; mechanism for arresting the rotation of said means when said scanner approaches a predetermined angular position comprising a member containing a projection mechanically biased against said means for engaging with said means to disengage said driving connection; a synchronizing magnet responsive to received cyclic synchronizing signals; and a weight positioned above

said member, releasable by said magnet against said member for cyclically rendering said arresting mechanism ineffectual in response to the synchronizing signals; and means for cyclically restoring said element above said member between 5 synchronizing signal conditions.

4. In a telepicture system, a motor; a scanner; a clutch connecting said motor and said scanner including a disc carried by said clutch for disengaging said clutch when said disc is held 10 against rotation; mechanism for arresting the rotation of said disc when said scanner approaches a predetermined angular position comprising a member containing a projection mechanically biased against the periphery of 15 said disc for engaging a notch on said periphery to disengage said disc; a synchronizing magnet responsive to received cyclic synchronizing signals; and means controlled by said magnet for moving said member projection away from said 20 periphery including a weight movable against said member, and an armature for said magnet containing a projection for supporting said weight above said member.

5. In a signalling system, a source of motive power; a rotatable member; a driving connection between said source of motive power and said rotatable member including a disc carried by said driving connection for disengaging said driving connection when said disc is held against rotation; mechanism for arresting the rotation of 25 said disc when said rotatable member approaches a predetermined angular position comprising a member containing a projection mechanically biased against said means for engaging with said 30 means to disengage said driving connection; a synchronizing magnet responsive to received cyclic synchronizing signals; and means controlled by said magnet for rendering said arresting mechanism ineffectual including a mass for impacting 40 against said member, and an armature for said magnet for supporting said mass above said member; and apparatus for cyclically raising said mass into engagement with said armature.

6. In a telepicture system, a motor; a scanner; a clutch connecting said motor and said scanner including a disc carried by said clutch for disengaging said clutch when said disc is held against rotation; mechanism for arresting the rotation of said disc when said scanner approaches a predetermined angular position comprising a lever containing a projection mechanically biased against the periphery of said disc for engaging a notch on said periphery to disengage said clutch; a synchronizing magnet responsive to received cyclic 55 synchronizing signals; means controlled by said magnet for moving said lever projection away from said periphery including a mass for impacting against said lever, and an armature for said magnet containing a projection for supporting 60 said mass above said lever; and apparatus for cyclically raising said mass into engagement with the projection of said armature.

7. In a telepicture system, a motor; a scanner; a clutch connecting said motor and said scanner including a disc carried by said clutch for disengaging said clutch when said disc is held against rotation; mechanism for arresting the rotation of said disc when said scanner approaches a predetermined angular position comprising a member containing a projection mechanically biased against the periphery of said disc for engaging a notch on said periphery to disengage said disc; a synchronizing magnet responsive to received cyclic synchronizing signals; means controlled by 75

said magnet for moving said member projection away from said periphery including a weight movable against said member, and an armature for said magnet containing a projection for supporting said weight above said member; and apparatus for cyclically raising said weight into engagement with said armature comprising a member, and a pin projecting from said disc, one end of said member coacting with said weight and the other end of said member being moved by said pin once per revolution of said pin.

8. In a telepicture system, a motor; a scanner; a clutch connecting said motor and said scanner including a disc carried by said clutch for disengaging said clutch when said disc is held against rotation; mechanism for arresting the rotation of said disc when said scanner approaches a predetermined angular position comprising a lever containing a projection mechanically biased against the periphery of said disc for engaging a notch on said periphery to disengage said clutch; a synchronizing magnet responsive to

received cyclic synchronizing signals; means controlled by said magnet for moving said lever projection away from said periphery including a weight movable against said lever, and an armature for said magnet containing a projection for supporting said weight above said lever; and apparatus for cyclically raising said weight into engagement with the projection of said armature comprising a pivoted member, and a pin secured to said clutch, one end of said member coacting with said weight and the other end of the said member being moved by said pin once per revolution of said pin, a rod for guiding the movement of said weight, said weight being raised on said rod by said member above said armature projection, a spring for biasing said armature towards said weight for retaining said weight in its upper position until released in response to a cyclic synchronizing signal whereby said scanner is connected to said motor in synchronous relation with said signals. 10 15 20

WILLIAM G. H. FINCH.
